TITRATION APPARATUS

Alexander I. Newman, Chicago, Ill., assignor to
 Precision Scientific Company, Chicago, Ill., a
 corporation of Illinois

Application June 24, 1940, Serial No. 342,039

2 Claims. (Cl. 23—253)

The invention relates to improvements in titration apparatus.

Customarily, titration tests are carried on by draining test liquids from successive burettes into a reaction receptacle and observing by means of graduations on the burettes, the quantity of test liquids which must be added to a reaction solution in the receptacle in order to bring about a predetermined reaction. For example, two burettes or graduated tubes may be loaded respectively with an alkaline solution and an acid solution, while a litmus solution, i. e., one which changes color upon a predominance of acid or alkali in contact with it, is placed in the reaction receptacle. The liquid is drained from one burette into the litmus solution until the latter changes color, whereupon the quantity of liquid which had to be added for this purpose is noted. Then the receptacle is placed under the other burette and liquid is drained from it into the receptacle until the litmus solution again changes color. As before, the amount of added solution necessary to bring about the reaction is observed.

Precision of results obtained with an apparatus of the character described above depends directly upon, first, the accuracy of the readings of the quantities of liquid withdrawn from the burettes, and, second, upon the accuracy with which the operator notes the precise point of visual change in the liquid in the receptacle, denoting that the reaction point has been reached. It will be appreciated that the graduations on the burettes are usually very fine, entailing considerable eye strain in reading them precisely, and, further, that the color changes or the like in the receptacle may at first be rather pale when the reaction first sets in, again requiring minute observation. Accordingly, the general aim of the present invention is to promote the accuracy of the results obtainable in such an apparatus, and a diminution in the strain on the operator, by virtue of the incorporation in the apparatus of a novel illuminating arrangement.

More specifically, it is an object of the invention to provide a titration apparatus embodying means for suffusing with bright light the burettes and reaction receptacle, as well as means forming a white background behind them, so that the graduations on the burettes will stand out in sharp relief and color changes in the receptacle contents will be easily observable, the lighting system being of the indirect type so that there is no glare directly in the user's eyes.

Another object is to provide a titration apparatus incorporating an indirect lighting system,

so correlated in a structural sense with the instrumentalities of the apparatus as to afford a compact unit and one which is also rugged in construction and low in cost.

Further objects and advantages of the invention will become apparent as the following description proceeds, taken in connection with the accompanying drawing in which:

Figure 1 is a general perspective view of a titration apparatus embodying the invention.

Fig. 2 is a transverse sectional view taken substantially along the line 2—2 in Fig. 1.

Fig. 3 is a general perspective view, though on a smaller scale than Fig. 1, of a modified form of titration apparatus also embodying the invention.

Fig. 4 is an enlarged transverse sectional view taken substantially along the line 4—4 in Fig. 3.

Although but two embodiments of the invention have been illustrated herein it will be apparent to those skilled in the art that various modifications and alternative constructions may be made to meet particular exigencies of use. Accordingly, it is to be understood that I do not intend to limit the invention by the particular disclosure made but aim to cover all modifications and alternative constructions falling within the spirit and scope of the invention, as expressed in the appended claims.

In the first illustrative embodiment of the invention (Figs. 1 and 2) the apparatus shown comprises a pair of burettes or graduated vertical tubes 10 having stop cocks 11 at their lower ends. Test liquids from alternate ones of these burettes are drained into a reaction receptacle shown as 12, a transparent glass beaker 12. The burettes themselves are also made of transparent glass so that the quantities of liquid withdrawn from them from time to time can be determined by reading the successive levels of the liquid shown by the graduations.

The burettes 10 are mounted on a structure which forms, first, a support for them, second, a light colored or white background to enhance the ease of observation of them, and, third, a reflector for diffusing light through the burettes and the receptacle 12. This structure comprises a hollow disk shaped sheet metal base 14. Rising from the rear of this base is a sheet metal reflector shield 15 which is generally channel shaped in cross section, in the present instance, semicircular. The burettes 10 are supported from the front face of this shield by releasable grip type spring clips 16 of well known form, and which are pivoted on the front face of the shield 55 on brackets 17 fixed to the latter.

As a source of illumination a fluorescent tube or tubular gaseous conduction lamp 18 is used. Suitable sockets 19 and 20 receive the upper and lower ends respectively of this lamp. The lower socket 20 is mounted on the base 14 while the upper socket 19 is carried on a bracket 21 fixed to the shield 15. A suitable reactor 22 for the lamp 18 may be mounted within the hollow base 14 and a plug type connector (not shown) provided for connecting the lamp to a source of current. A tumbler switch 23 at the front of the base is used to turn the lamp on or off.

The lamp 18 is located centrally in front of the shield 15 and within its confines as best shown in Fig. 2. Thus the lamp lies on a radius from the center of the base passing through the center of the shield 15. On the other hand, the burettes 10 are located one on each side of the lamp 18 and somewhat forwardly of it. The relative location of the lamp and burettes is so chosen that light from the lamp will be reflected by the shield 15 on to the burettes, the latter being disposed close to the focal centers of the illuminating system as shown by the dot-dash lines L in Fig. 2. The burettes are also illuminated by light falling directly on them from the lamp 18 as well as by the reflected light noted. The illumination is, in fact, so complete with the present apparatus as to afford a very close approximation of daylight conditions. In addition, the exact shape of the reflector shield is not critical since accurate direction of light rays cannot be obtained from a fluorescent lamp, anyhow, a general suffusion of light over the parts illuminated being obtained.

To prevent light from the lamp 18 glaring in the operator's eyes, an opaque guard strip or screen 24 is positioned in front of the lamp. The lower end of the strip is fixed to the base 14 while its upper end is carried by a forwardly projecting bracket 25 on the shield 15. The guard strip 24 not only effectually intercepts light rays which would otherwise pass directly to the observer's eyes but also reflects them back to the shield 15 where they are in turn reflected to the burettes, the inside of the strip 24 being desirably white for that purpose.

In order to form a noninterfering background for the burettes 10 and beaker 12 the inside or front surface of the shield 15, as well as the top of the base 14, are preferably white. Such a white surface affords a good contrast to the color of the liquids in the burettes as well as to the color of the reaction solution in the beaker 12. In addition, such white surfaces have a low degree of light absorption, or, in other words, constitute good reflecting surfaces for reflecting light from the tube 18 onto the burettes and receptacle.

In the use of the titration apparatus described, a quantity of acid solution may be placed in one of the burettes 10 and a quantity of alkaline solution in the other. The solution being tested is placed in the beaker 12 and the initial quantities of solution in both the burettes are, of course, noted. This is done with the lamp 18 turned on so that the entire interior of the apparatus is suffused with light and the burettes, as well as the receptacle 12, fully illuminated. The beaker 12 is then placed beneath, say, the right hand burette, as shown, and the stop cock 11 for this burette opened so that the solution from the burette is slowly drained from the receptacle. Such draining of the solution is continued until the operator observes a color change or other

desired reaction in the beaker. Thereupon he shuts off the stop cock and observes the amount of liquid withdrawn from the burette, to bring about the reaction, as indicated by the change in level of the solution in the burette. Then the beaker 12 may be shifted to a point beneath the other burette and the operation repeated. This general type of operation is, of course, familiar, the improvement in operation herein obtained lying in the ease and accuracy with which the readings of solution level in burettes may be read and the reaction changes in the beaker noted.

A modified form of titration apparatus also embodying the invention has been shown in Figs. 3 and 4. In this instance a pair of burettes 10, identical with those described above are also provided, as is a beaker 12. To illuminate these instrumentalities, however, two fluorescent lamps 18, rather than one, are now used. In this case the base 14a is generally like the base 14, previously described, except that it is elliptical rather than circular in shape. This is done in order that a shield 15a rising from it may present a front surface of parabolic, rather than semi-circular cross section, this difference in shape being desirable when using two sources of illumination disposed laterally of the burettes and at the points indicated in Fig. 4.

One advantage of the modified construction shown in Figs. 3 and 4, is that the screening of the lamp, to prevent glare in the operator's eyes, is accomplished simply by bending the front edge portions 15b of the shield 15a inward about the fronts of the lamps 18 rather than providing a separate guard structure for the purpose.

The operation for the apparatus of Figs. 3 and 4 is substantially identical with that heretofore described for Figs. 1 and 2. As before, the burettes 10 and beaker 12 are fully illuminated for precision observation, being suffused with light from the indirect lighting source so that they can be readily observed and, yet, there will be no glare of light in the operator's eyes. In both instances the apparatus is very compact, low in cost, and of such form that it can be readily handled as a unit both in merchandising and during its use in the laboratory.

I claim as my invention:

1. In a titration apparatus, the combination of a base, a vertical sheet metal shield of substantially half round cross section rising from the base of the rear side thereof, a forward projection at the top of the shield, a fluorescent electric lamp of tubular form supported in upright position between said projection and the base with the longitudinal axis of the lamp displaced toward the center of the base from the shield and lying substantially on a radius of the base projecting toward the center of the shield, means for supporting a pair of burettes one on each side of the lamp directly in front of the shield and at points close to the focal points of light falling on the respective halves of the shield, the forward face of the shield and the top of the base being substantially white to form a non-interfering and low light absorption background, and an opaque strip fixed to said base in front of the lamp to cut off direct glare from the lamp into the eyes of an observer stationed in front of the apparatus.

2. In a titration apparatus, the combination of a base, a vertical sheet metal shield of generally curved cross section rising from the base at the rear side thereof and presenting a concave forward face, a fluorescent electric lamp of tubular

form supported in upright position in front of a portion of said shield and above said base, means for supporting a pair of burettes in upright position in front of said shield in parallel spaced relation to each other and to said lamp with at least one of said burettes disposed close to a focal point of the light reflected by said shield from said lamp, the forward face of the shield and the

5 top of the base being substantially white to form a non-interfering and low light absorption background, and an elongated upright opaque barrier rigid with said shield and positioned in front of the lamp to cut off direct glare from said lamp into the eyes of an observer stationed in front of the apparatus.

ALEXANDER I. NEWMAN.
